ATTORNEY

UNITED STATES PATENT OFFICE.

MARTIN G. SCHLACHT, OF TUCSON, ARIZONA.

MAIL-BAG-TRANSFERRING DEVICE.

1,284,469.

Specification of Letters Patent. Patented Nov. 12, 1918.

Application filed May 9, 1918. Serial No. 233,549.

To all whom it may concern:

Be it known that I, MARTIN G. SCHLACHT, a citizen of the United States, residing at Tucson, in the county of Pima and State of Arizona, have invented certain new and useful Improvements in Mail-Bag-Transferring Devices, of which the following is a specification.

This invention relates to mail bag handling apparatus adapted for effecting an automatic transfer of mail or other packages to and from moving trains, and it has for its primary object to provide an apparatus of this character which will be simple in construction, positive in operation, and absolutely reliable in use.

A further object of the invention is to provide a device for handling mail bags which prevents the bags from coming in contact with the ground, and which causes the interchange of mail bags in such manner as to minimize the opportunity for wear of the bags or damage to the contents thereof.

A still further object of the invention resides in providing a receptacle for the purpose of receiving the bags and which is equipped with improved means for causing the automatic closing of the receptacle when the bag has been delivered thereto, and which is equipped with means operable by the movement of the bag for properly centering the latter within the receptacle.

With these objects in view together with others which will appear as the description proceeds, the invention resides in the novel formation, combination and arrangement of parts, all as will be described more fully hereinafter, illustrated in the drawings, and particularly pointed out in the claims.

In the drawings:

Figure 1 is a front elevation of a receptacle for the mail bags, the receptacle being shown in open position.

Fig. 2 is a horizontal sectional view taken upon line 2—2 of Fig. 1, and

Fig. 3 is a similar view taken upon line 3—3 of Fig. 1.

Referring now more particularly to the drawings, 5 represents a post or standard mounted beside the railroad tracks, and which is adapted to support the receptacle of my invention.

The receptacle comprises a pair of semi-cylindrical sections 6 and 7, each of said sections being closed at its end as shown, and

these sections are adapted when placed together edge to edge to constitute the holder for a mail bag. Each of the sections 6 and 7 is provided adjacent one edge with outwardly projecting arms 8 and 9, the said arms being rotatably secured upon the standard 5. Collars 10 are affixed to the standard and support the arms 8 and 9, and it is obvious from the structure described, that the sections 6 and 7 are capable of rotating upon the said standard.

The arm 9 is provided adjacent its outer end with a shoulder 11, engaged by a pawl 12 carried by the arm 8, and the pawl is yieldably held in engagement with the shoulder 11 by a spring 13. The shoulder is arranged upon the arm in such manner that the pawl 12 will be engaged therewith when the sections 6 and 7 are in open position, or in a position to receive the mail bags from a moving train. A bracket 14 is permanently secured at one end to the section 6 and has its free end disposed in the path of movement of the section 7, and limits the movement of the said sections in one direction.

Pivoted at one end within the section 6 is a trip lever 15, the free end of the said lever being connected by a flexible member 85 such as a cord or chain 16, with the pawl 12, and it is obvious that when the trip lever is moved in one direction, the cord 16 will be tensioned so as to draw the pawl 12 out of engagement with the shoulder 11. Interposed between the sections 6 and 7, are springs 17. In the present instance, these springs are shown as being coiled around the standard 5 and being engaged at their ends with the rear faces of the sections 6 and 7, thus normally forcing the sections into engagement with each other. The construction is such that when the sections 6 and 7 have been moved outwardly until the pawl 12 engages the shoulder 11, the receptacle will be in "cocked" position, and the springs 17 will be tensioned.

Should a mail bag be thrown into the section 6, it will contact the trip arm 15, whereupon the pawl 12 will be withdrawn from engagement with the shoulder 11 and the springs 17 will be permitted to force the section 7 into closed position. It will be observed that when in closed position, the edges of the section 7 will be engaged with the corresponding edges of the section 6 and the mail bags will thus be wholly inclosed.

105
110

The receptacle is placed beside the track, relatively close to the moving train, and when in open or receiving position, section 6 is disposed next to the moving train and is 5 in a position to receive a bag delivered or thrown therefrom. When the bag enters the section 6, the momentum thereof will force the said section rearwardly, and this force will be transmitted to the section 7 through 10 the brace or bracket 14, causing the section 7 to be thrown forwardly. It will be understood, that this force is not imparted to the section 7 until after the pawl 12 has been disengaged from the shoulder 11. The section 15 7 swings over the section 6, and the bolt 20 thereof enters the lock casing 21, causing the said sections to be locked together. The mail clerk may open the receptacle by inserting the proper key in the lock casing 21, as will 20 be understood. The force of the bag contacting the section 6, will cause the casing or receptacle to rapidly rotate upon the standard 5, and the momentum of the bag is thus gradually dissipated.

25 To prevent the bag delivered to the receptacle section 6 becoming engaged with the edges thereof, or being dropped into a position to prevent the section 7 closely fitting upon the section 6, the last mentioned section 30 is provided upon its inner face with centering members constituting the arms 23. These arms are pivoted intermediate their ends as at 24, to the interior of the section and each of the said arms is provided with a substantially right angularly disposed portion 25 against which the mail bag is adapted to engage. A spring tends to force the portion 25 rearwardly into the casing and to move the portion 23 outwardly into the center of the 40 casing and a snap fastener such as the spring indicated at 27 is employed to hold the centering arms in operative position. When the bag is thrown into the section, the same comes into contact with arm 23, whereupon the 45 force delivered thereto will cause the arm 23 to spring past the snap fastener or spring 27. The arm 23 thus will be forced by spring 26 toward the center of the section, and the bag will be carried by the said arm and kept out 50 of engagement with the outer edges of the casing section.

The bags delivered from the train may be supported upon suitable arms or may be tossed into the section 6 from the doorway 55 of the car.

The above is a description of the receptacle for the mail bags and is described as being positioned upon the ground, but it will be understood that a similar device could be 60 positioned upon the car to receive mail bags

suspended beside the track. It is obvious that with the use of a device of this character, the mail bag interchanged, will be prevented from coming into contact with the ground and will be delivered to the receptacle in such manner as to minimize the opportunity for wear or breakage of the bags or contents thereof.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent, is:—

1. In a device of the class described, a receiver comprising a pair of sections hinged together, means tending normally to force said sections together, a pawl for holding said sections against said forcing means, a trip mechanism in one of said sections, a connection between said trip mechanism and said pawl, and a bracket connected to one of said sections and engaged by the other of said sections when the said sections are in open position.

2. In a device of the class described, a standard, a pair of sections, arms projecting from the adjacent edges of said sections and being rotatably supported upon said standard, a shoulder on one of said arms, a pawl carried by the adjacent arm of the next section, the pawl engaged with said shoulder when said sections are separated, a trip lever in one of said sections, a flexible member connecting said trip member with said pawl, and a spring interposed between said sections and tending to force the same together.

3. In a device of the class described, a receiver comprising a pair of hinged sections, centering arms arranged within one of said sections, an arm connected to each of said centering arms and disposed across said section and away from the wall thereof, a spring tending normally to force said centering arms toward the center of said section, and a spring latch for holding said arms retracted.

In testimony whereof I affix my signature in presence of two witnesses.

MARTIN G. SCHLACHT.
